UNITED STATES PATENT OFFICE.

HENRY A. RUDD, OF BARBERTON, OHIO, ASSIGNOR OF ONE-HALF TO MICHAEL PARIDON, OF BARBERTON, OHIO.

PNEUMATIC-TIRE SHOE.

1,200,031.

Specification of Letters Patent.

Patented Oct. 3, 1916.

Application filed May 15, 1916. Serial No. 97,586.

To all whom it may concern:

Be it known that I, HENRY A. RUDD, a citizen of the United States, residing at Barberton, in the county of Summit and 5 State of Ohio, have invented new and useful Improvements in Pneumatic-Tire Shoes, of which the following is a specification.

This invention relates to improvements in the construction of tire-shoes for pneumatic-tires and has a special relation to improvements in the construction of the bead portions thereof.

The object of the invention is to provide an improved core adapted for incorporation 15 within the bead of a pneumatic-tire-shoe which will strengthen the same and serve as a means for spacing the cords from which a tire-shoe may be constructed.

It is contemplated as a further object that 20 the device is especially applicable for use in a tire-shoe wherein the strength-giving properties of the shoe comprise one or more layers of cord to form what is commonly known as a cord-tire.

Another object of the invention is to 25 provide a core for beads for use in pneumatic-tire-shoes provided with a pair of annularly formed bands adapted to be connected or drawn toward each other upon an interposed layer of fabric having a tapering edge against which the cords of the tire-shoe can engage and to which they will readily adhere by employment of the usual vulcanizable adhesive used in the construction 35 of tire-shoes.

With the foregoing and other objects in view, the invention consists in the novel construction, combination and arrangement of parts constituting the invention to be hereinafter specifically described and illustrated in the accompanying drawings which 40 form a part hereof wherein is shown the preferred embodiment of the invention, but it is to be understood that changes, variations and modifications can be resorted to 45 which come within the scope of the matter hereinafter claimed.

In the drawings in which similar reference numerals indicate like parts in the different figures, Figure 1, is a transverse sectional view of the bead-portion of a tire-shoe embodying this invention. Fig. 2, is a side elevation of a bead-core embodying this invention. Fig. 3, is a perspective view of 55 the core shown in Fig. 2, and Fig. 4, is a

view partially in section and partially in side elevation of so much of the bead portion of a pneumatic-tire-shoe as will illustrate the present invention.

The core which forms the subject matter 60 of this invention comprises two annularly formed members or rings 1 and 2 provided with registering openings through which are extended clamping or holding members, such for instance as rivets 3. The inner 65 faces of the two members 1 and 2 are provided with teeth or notches 4 providing between them spaces 5 for a purpose to be later described. Interposed between the two members 1 and 2 is a body member of 70 fibrous material such as cloth 6 which may be arranged in successive layers or otherwise but preferably so fashioned as to be wedge-shaped in cross section as shown in Figs. 1 and 3. This cloth will ordinarily 75 be impregnated with a vulcanizable gum compound so as to adhere to the cord portions of the tire-shoe when the shoe is vulcanized. The notches between the teeth 4 constitute retaining means for the cords 7 80 of which the body portion of the tire-shoe is formed so that as the cords 7 are carried or laid in the formation of the bead of the tire they will extend inwardly from the tread portion of the tire and across the two 85 members 1 and 2, seating in appropriate notches 5 of the members 1 and 2 and thence outwardly to the tread as shown in Fig. 4, but of course, usually at an angle approximating 45 degrees to the longitudinal line 90 of the shoe to form a single layer. The convolutions of cords 7 about the core formed by the members 1, 2, and 6 will form the base or nucleus of the bead of the tire about which other bead material may be 95 employed as shown in Fig. 1. By making the members 1 and 2 of relatively thin material and clamping them against the fibrous material 6 which is relatively thin and containing a vulcanizable material 100 the two layers of cords forming the body portion of the tire will be brought closely together and the cords or members which form the strength-giving properties of the tire will unite with the fibrous members 6 105 during vulcanization and hence no gaps or openings will exist between the two layers of cords outside of the reinforcing core members 1 and 2 and all portions of the body of the shoe will hence be intimately 110

united which would not be true if the interposed layer of material 6 was not employed.

In ordinary practice if a reinforcement or core is provided in the bead portion of the shoe and strength-giving cords are arranged as shown in Fig. 4 the portions of the cords immediately outside of the core will always remain in spaced relation thereby providing 10 an air space, which prevents adhesion or close contact of the two layers of the body portion of the shoe. The space between the two layers immediately outside of the core is a source of weakness which is entirely 15 eliminated by the use of a core forming the present invention, the interposed strip of fibrous material 6 serving to fill this space and affording means to which the two layers of cords are intimately united during vul- 20 canization.

I claim,

1. A pneumatic-tire-shoe provided in each bead portion with a pair of ring-shaped members arranged in spaced relation and 25 connected together, a layer of fibrous material extending in a circumferential direction only positioned between said members and held in position by the means connecting said ring-shaped member.

30 2. A reinforcement for a pneumatic-tire-shoe bead comprising a pair of ring-shaped inextensible bands adapted to be connected by transversely-extending members and an interposed fibrous band extending in a cir- 35 cumferential direction only between them and held in position thereby.

3. A reinforcement adapted to be incorporated in the bead portion of a pneumatic-tire-shoe comprising a pair of metallic rings 40 between which is interposed an outwardly projecting ring of fibrous material impregnated with a vulcanizable compound, and fastening means extending between said metallic bands for holding said fibrous band 45 in position.

4. A reinforcement for pneumatic-tire-shoe beads comprising a pair of ring-shaped metallic bands, an interposed annular band of fibrous material impregnated with a vul- 50 canizable compound, clamping means ex- tending between said metallic bands for

clamping said bands against said fibrous band.

5. A reinforcing core for a bead of a pneumatic-tire-shoe comprising two ring-shaped bands of inextensible material and a band of fibrous material interposed between them and projecting outwardly therefrom, means extending through said bands for holding them in assembled relation. 60

6. A reinforcing core for a bead of a pneumatic-tire-shoe, comprising two ring-shaped bands of inextensible material, a band of fibrous material interposed between them and projecting outwardly therefrom and means extending through said bands for holding them in assembled relation, the inner faces of said inextensible bands provided with a circumferentially-extending 65 series of notches. 70

7. A reinforcing core for use in connection with a bead of a pneumatic-tire-shoe which comprises two inextensible bands arranged in spaced relation, an interposed band of fibrous material, means for clamping said inextensible bands on said fibrous band, said inextensible bands each provided on their inner faces with a circumferentially-extending series of notches. 75

8. A reinforcing core for use in connection with a bead of a pneumatic-tire-shoe which comprises two inextensible bands arranged in spaced relation, an interposed band of fibrous material, means for clamping said inextensible bands on said fibrous band, said inextensible bands provided on their inner faces with circumferentially-extending series of notches, said notches constituting holding means for cords used in forming the body portion of said tire-shoe. 80 90

9. A pneumatic-tire-shoe having in the bead portion thereof a pair of annularly-fashioned reinforcing elements of inextensible material, an annular band of fibrous material wider than said elements interposed 95 between them, and coupling means for clamping said elements against opposite faces of said fibrous band.

In testimony whereof I have hereunto set my hand.

HENRY A. RUDD.
